United States Patent Office

Des. 218,626
Patented Sept. 8, 1970

218,626

TOY BANK

Robert F. Bateman, Providence, R.I., and Thomas E. Brown, Birmingham, Mich., assignors to Dart Industries Inc., a corporation of Delaware

Continuation of design application Ser. No. 2,541, June 3, 1966. This application Nov. 16, 1967, Ser. No. 9,448

Term of patent 14 years

Int. Cl. D21—02

U.S. Cl. D34—11

FIG. 1

FIG. 2

FIG. 6

FIG. 3

FIG. 4

FIG. 5

FIG. 1 is a front elevation view of a toy bank showing our new design;

FIG. 2 is a top plan view thereof;

FIG. 3 is a bottom plan view;

FIG. 4 is a rear elevational view;

FIG. 5 is a side elevational view; and,

FIG. 6 is a view in cross-sectional elevational taken along lines 6-6 of FIG. 2 and showing details of the design and appearance of the toy bank.

The dominant features reside in the full line portions shown.

This application is a continuation of D. 2,541 filed June 3, 1966, and now abandoned.

We claim:

The ornamental design for a toy bank, substantially as shown and described.
